HAIR CURLER

Esther I. Edwards, Brooklyn, N. Y.

Application November 20, 1937, Serial No. 175,658

7 Claims. (Cl. 132—31)

This invention relates to new and useful improvements in toilet devices, and more particularly it pertains to devices for curling the human hair.

5 It is the object of the invention to improve the construction and operation of such devices generally and to provide a novel hair curler which may be worn with greater comfort than such devices with which I am familiar.

10 A feature of the invention resides in the use of a relatively soft pliable material which will permit of more comfort in wear than is possible with such devices as they are generally constructed.

15 Another feature of the invention resides in a novel construction which will permit the device to conform generally to the shape of the head of the wearer without discomfort.

Still another feature of the invention resides 20 in a novel construction an arrangement of parts whereby, the so-called end curl or ringlet curl as distinguished from the marcel and other types of curl known generally as waves.

Other objects of the invention will become apparent as the nature of the invention is better understood, and reference will now be had to the following specification and claims, and the accompanying drawing wherein,

25 Figure 1 is a view showing the preferred manner of use of a hair curler constructed in accordance with the present invention.

Figure 2 is a perspective view of the hair curler,

30 Figure 3 is a transverse sectional view, taken substantially on the line 3—3 of Figure 2, and;

35 Figure 4 is an edge view, showing the manner in which the device may be flexed to conform to the shape of the head of a wearer.

Referring specifically to the drawing, a curler 40 constructed in accordance with the present invention comprises an elongated, relatively thin and narrow body portion which is designated 10, in the drawing.

Extending from one only of the flat faces of 45 said body portion, there is a plurality of shank-like projections 12 and upon the outer or free end of each of said projections 12, there is a head 14.

The body portion 10, the projections 12, and the heads 14, all form an integral structure and are formed from a relatively soft and pliable material, of which the so-called sponge rubber is one very good example.

50 The body portion, as above stated, is relatively thin and narrow and of general rectangular form, having two flat faces 16 and 18. Such a

body portion, when formed of relatively soft, pliable material may be flexed as shown in Figure 3, and is, therefore, readily conformable to the head of the wearer.

The shank-like projections extend from the 5 flat face 16, and, although such an arrangement is not necessary, I prefer to arrange them in equi-distantly spaced relation to one another.

As will be apparent from the drawing, the projections 12 are of circular cross-sectional form. 10 These projections taper from one end to the other and are more clearly shown in Figure 3, as having their thickest portion 20 at the point of juncture with the body portion 10, and with the portion of least diameter at the outer end where the 15 projection 12, merges into the head 14.

The head 14, is thickest at its central portion as indicated in Figure 3, and its outer face 22 is curved or convex as shown. The head is of circular form and its convex outer face is defined 20 by a marginal edge 24, which merges into a relatively flat under face 26.

By this construction, ample space is provided to wind the hair about the projections 12, between their respective heads and the body portion 16 of the device.

In use, the hair is, as shown in Figure 1, divided into locks or strands A, which are wrapped circumferentially around the projections 12, there preferably being one lock wrapped around each 30 projection as shown. In wrapping the lock of hair around the projections 12, the device is so positioned with respect to the head of the wearer, that the flat face 18 of the body portion 10, will be next to the head, as shown in Figure 1, and 35 when worn in this manner, owing to the fact that the flat face 18 of the body portion is next to the head with the projections upon the outer side of the body portion, no discomfort upon the part of the wearer will be had, even though the 40 device is worn while sleeping, since, as heretofore stated, the body portion 10, may conform to the shape of the head of the wearer and owing to the material used, and the general construction employed, pressure applied to the projections 45 cannot be transmitted through the body portion 10 of the device, to the head of the wearer.

The locks A, of hair may be wrapped about the projections 12 as tightly as desired, depending upon the type of curl desired, and after the 50 wrapping has been completed, the free ends of the hairs of the locks or strands may be retained in proper position, by a relatively small hair pin, ribbon or tape, or in any desired manner.

From the foregoing, it will be readily apparent 55

that the present invention provides a new and improved hair curler by means of which side curls or ringlets as distinguished from waves, may be formed. Furthermore, the invention provides a device which may be worn with ease and comfort and which may be readily attached and removed with but little effort.

10 While the invention has been herein illustrated in its preferred form, it is to be understood that it is not to be limited to the construction herein illustrated, and that it may be carried out in such other forms as rightfully fall within the scope of the appended claims.

Having thus described the invention, what is claimed as new, is:

1. A hair curling device comprising a body portion of soft pliable material, a plurality of integral projections extending from one face of the body portion, the opposite face of the body portion being adapted to lie flatly against and conform to the shape of the head of a person and a head carried by and integral with each of said projections, each of said projections constituting a curl former for forming individual curls thereon. 20

2. A hair curling device comprising an elongated relatively thin body portion of soft pliable material, a plurality of equi-distantly spaced projections extending from one face of said body portion, the opposite face of the body portion being adapted to lie flatly against and conform to the shape of the head of a person and a head forming the free end of each of said projections, each of said projections constituting a curl former for forming individual curls thereon. 25

3. A hair curling device comprising an elongated relatively thin and narrow body portion of soft pliable material, a plurality of projections of circular cross-sectional form extending from one of the flat faces of said body portion, the opposite face of the body portion being adapted to lie flatly against and conform to the shape of the head of a person and a head integral with each of said projections, said heads each being round and having a convex outer surface, each of said projections constituting a curl former for forming individual curls thereon. 30

4. A hair curling device comprising an elongated relatively thin and narrow body portion of soft pliable material, a plurality of projections of circular cross-sectional form extending from one of the flat faces of said body portion, the opposite face of the body portion being adapted to lie flatly against and conform to the shape of the head of a person and a head integral with each of said projections, each of said projections being thickest at its base or point of juncture with the body portion, and a head upon the free end of each of said projections and formed integral therewith, each of said projections constituting a curl former for forming individual 35

curls thereon. 40

5. A hair curling device comprising an elongated relatively thin and narrow body portion of soft pliable material, a plurality of projections extending from one of the flat faces of said body portion, the opposite face of the body portion being adapted to lie flatly against and conform to the shape of the head of a person each of said projections being of circular cross-sectional form and being thickest at its base or point of juncture with the body portion, and a head upon the free end of each of said projections and formed integral therewith, said heads being of circular form and being thickest at the axis thereof, each of said projections constituting a curl former for forming individual 45

curls thereon. 50

6. A hair curling device comprising an elongated relatively thin and narrow body portion of soft pliable material, a plurality of projections extending from one of the flat faces of said body portion, the opposite face of the body portion being adapted to lie flatly against and conform to the shape of the head of a person each of said projections being of circular cross-sectional form and tapering from one end to the other, and a circular head integral with the free end of each of said projections, said heads each having a convex outer face, and a rounded edge merging into a relatively flat inner or under face, each of said projections constituting a curl former for forming individual 55

curls thereon. 60
